[57] CLAIM

The ornamental design for a conveyor rail, as shown and described.

DESCRIPTION

FIG. 1 is a top plan view of a conveyor rail, my new design.

FIG. 2 is a front elevational view thereof.

FIG. 3 is a right side elevational view thereof, the left side view being a mirror image of that shown;

FIG. 4 is a bottom plan view thereof.

FIG. 5 is a rear elevational view thereof.

FIG. 6 is a top plan view of a second embodiment of the conveyor rail, a portion thereof being broken away to indicate indeterminate length. The sole difference from the first embodiment being its indeterminate length;

FIG. 7 is a front elevational view of FIG. 6.

FIG. 8 is a bottom plan view of FIG. 6.

FIG. 9 is a rear elevational view of FIG. 6.

The left and right side of the second embodiment is the same as in FIG. 3.
